UNITED STATES PATENT OFFICE.

JOSIAH L. MERRILL, OF MEDIA, PENNSYLVANIA.

CONDENSER.

Application filed July 5, 1924. Serial No. 724,456.

This invention is an electrical condenser constructed to prevent electrical losses at the points where the leads are joined with the conductor material of the condenser structure.

Heretofore it has been common practice to construct electrical condensers of alternate layers of dielectric material and conducting material. These two materials are assembled by various methods, ordinary paraffin-coated paper being commonly used as the dielectric, and tin foil or the like, as the conductive material. In condensers of this type however, a serious problem is presented in properly uniting the leads which extend to the condenser terminals, with the conductive material. The usual practice is to attach fine wires to the foil in various ways, and having said wires extended laterally from the foil so that they may be connected to the condenser terminals. Owing to the thinness of the tin or aluminum foil, or the like, it is practically impossible to obtain anything like a perfect connection between the wire lead and the foil, and as a consequence the efficiency of the finished condenser is materially lowered by reason of the leakage at such points of union.

One of the objects of the invention is to overcome the foregoing objections, by providing a condenser having its leads so constructed as to practically avoid electrical loss at the points where the leads extend from the electrical material. A further object is to provide layers of tin or aluminum foil, or the like, having terminal portions shaped to provide integral leads, whereby joints between the leads and the foil are avoided and a maximum efficiency is assured.

The invention will be hereinafter fully set forth and particularly pointed out in the claims.

In the accompanying drawing:

Figure 1 is a perspective view illustrating an electric condenser, constructed in accordance with the invention, portions of the electric and dielectric elements being unrolled. Figure 2 is a diagrammatic view illustrating the method of forming the condenser lead. Figure 3 is a similar view of a slight modification.

Referring to the drawing, 10 designates a sheet of tin or aluminum foil, and 11 a sheet of paraffin-coated paper, which sheets are rolled together and flattened, as indicated at 13. It is to be understood that the foregoing arrangement is shown and described

merely for illustrative purposes, for the reason that the invention is not limited either to the shape of the condenser, or the number of layers of electric and dielectric material, or the relative number of sheets of dielectric material with respect to the sheets of tin or aluminum foil.

The end of the foil sheet 10 is consecutively folded back upon itself in a diagonal position, a number of times, as indicated at 14, to form a plurality of layers 15, with the extremity or raw edge of the sheet enclosed within the fold. The effect of the folding as thus described, is to cause a narrowly folded portion 16 of the foil to extend diagonally and laterally beyond the upper edge of the foil sheet, the extremity of the sheet being turned in and protected in a manner that will prevent it from being torn (see Figure 75 2). The lateral extended portion 16, is twisted, rolled, or otherwise shaped for ready and convenient connection with the usual terminal of the condenser, and bent at an angle parallel with the faces of the sheet material.

In lieu of folding the sheet 10 to provide the lateral extension, it may be rolled as indicated at 17, Figure 3, and then flattened to produce the folds.

From the foregoing it will be readily seen that joints between the condenser leads and the electric material are avoided and that this effect is obtained by producing an integral extension of the tin or aluminum foil sheet, and shaping it to form the condenser lead. By this means the expense of manufacture is not at all increased, and yet a maximum efficiency due to the reduction of electric losses at those points where the leads extend from the foil sheets is assured.

Having thus explained the nature of the invention and described an operative manner of constructing and using the same, although without attempting to set forth all of the forms in which it may be made, or all of the forms of its use, what is claimed is:

1. A condenser of the character described comprising sheets of dielectric material and sheets of metal foil, one end of each foil sheet having an integral condenser-lead-extension formed of a portion of the sheet wound upon one corner of the said end in a diagonal line extending transversely of the sheet, so that said corner lies within the innermost fold and is enclosed and covered by the successive folds which are wound around it.
2. A condenser of the character described

comprising sheets of dielectric material and
sheets of metal foil, one end of each foil sheet
having an integral condenser-lead-extension
formed of a portion of the sheet wound upon
5 one corner of the said end in a diagonal line
extending transversely of the sheet, so that
a portion of the wound portion projects be-
yond one edge of said sheet, and said corner
lies within the innermost fold and is enclosed
10 and covered by the successive folds which are
wound upon it, said projecting portion being
disposed at an angle to the rest of the lead and
also with respect to said sheet.

3. A condenser of the character described
15 comprising sheets of dielectric material and

sheets of metal foil, one end of each foil sheet
having an integral condenser-lead-extension
formed of a portion of the sheet wound
around one corner of the said end in a diag-
onal line extending transversely of the sheet, 20
so that a portion of said condenser lead ex-
tends beyond one edge of said sheet, and said
corner is enclosed and covered by the suc-
cessive folds which are wound around it, the said
projecting portion having a twisted forma- 25
tion.

In testimony whereof I have hereunto set
my hand.

JOSIAH L. MERRILL.
